CHRYSANTHEMUM PLANT

Keith D. Butters, Littlehampton, England, assignor to
Yoder Brothers, Inc., Barberton, Ohio
Filed Apr. 3, 1972, Ser. No. 240,859
Int. Cl. A01h 5/00

U.S. Cl. Plt.—74

1 Claim

The present invention comprises a new and distinct cultivar of daisy form chrysanthemum plant which is a sport of the unpatented cultivar known commercially in the United States as Bronze Marble.

The new cultivar is similar in many respects to Bronze Marble, having the same characteristics of:

- (1) Flower size.
- (2) Daisy flower form.
- (3) Plant habit.
- (4) Recommended period of flowering.
- (5) Foliage shape and size.

The new cultivar is distinguished from Bronze Marble, when grown under comparable conditions, by its darker, more intense bronze color.

The new cultivar was selected from a flowering block of the parent cultivar at Littlehampton, Sussex, England, and when asexually reproduced by cuttings at Littlehampton, Sussex, England, has been found to retain its distinctive characteristics through successive propagations.

Botanical classification: *Chrysanthemum morifolium*

	Gay Marble	Bronze Marble
Bloom:		
Size:	Approximately 2 3/4"	
Fully expanded:	Approximately 3 1/4"	
Borne:	In compound lateral clusters of 5 to 8 flowers	
Stems:	Wiry	
Form:	Daisy	
Permanence:	7 days	
Color:		
Center of flower	Light green, 2, 5GY5/8 to dark yellow, 6.25Y8.5/12	Light green, 2.5GY5/8 to dark yellow, 6.25Y8.5/12
Base of petals	Yellow 7.5Y8.5/10	Yellow, 7.5Y8.5/10
Inside of petals	Red bronze, 2.5YR4/10 to light orange bronze, 7.5YR6/8 over yellow, 2.5Y8/8	Orange bronze, 5YR6/10 over yellow, 2.5Y8.5/8
Reverse of petals	Yellow, 5Y8.5/10 to buff, 7.5YR6/8 over yellow, 2.5Y8/6	Yellow, 5Y8.5/10 to buff, 7.5YR6/8 over yellow, 2.5Y8/6
Tonality from a distance	Bronze	Orange bronze
Discoloration	Light orange bronze, 7.5YR6/8 over yellow, 2.5Y8/6	Light orange bronze, 7.5YR6/8 over yellow, 2.5Y8/6
Petals:		
Texture	Smooth	
Appearance and form	Open at base, broad at mid-point, tapering to a blunt point	
Arrangement	Composite, whorled on a single receptacle	
Persistence	Resist shatter	
Fragrance	Typical chrysanthemum	
Reproductive organs:		
Stamens, anthers	200-250	
Pollen	None to abundant (functional sterility)	
Arrangement	Clustered in center of flower, if present	
Styles	Present both ray and disc florets	
Length	Short	
Ovaries	At the base of petal attached to receptacle	
Plant:		
Form	Herbaceous	
Growth	Upright	
Height	Approximately 42" to 47" on single stem crop given 3-5 long day weeks and 12-14 weeks total crop time as designated in the timetables of Yoder Brothers, Inc., Barberton, Ohio.	Approximately 42" to 47" on single stem crop given 3-5 long day weeks and 12-14 total crop time as designated in the timetables of Yoder Brothers, Inc., Barberton, Ohio.
Spread	None when grown single stem to moderate when pinched	
Foliation:		
Top side	Dark green, 7.5GY3/4	
Size	5 1/2" long, 3 1/4" wide	
Quantity	Numerous	
Shape	Spatulate lobed	
Texture	Smooth	
Ribs & veins	Prominent	
Edge	Moderately indented	
Serration	Moderate	
Under side	Light green, 7.5GY5/4	
Stipules	Prominent	

The new cultivar when grown in the vicinity of Barberton, Ohio, has a response period of approximately 9 weeks, and the following detailed description is based on observations made of the new cultivar in a greenhouse in Barberton, Ohio. The response time, blooming period, color, and total vigor may vary significantly with varying environmental conditions such as temperature, daylength,

65 2

and light intensity. Suggested flowering of the new cultivar in the northern and western United States is from April through October; in coastal California, January through December; and in Florida, December through April.

5 The accompanying photographic drawing shows the unique color of the new cultivar, the color being as nearly true as possible with color illustrations of this type. In the drawing, which comprises a closeup view of the flowers of the new and parent cultivars, the new cultivar appears on the left and the parent comparison cultivar appears on the right.

10 In the description which follows, color references are made to the Munsell Color Book, 1963 edition, and comparisons are made with the parent cultivar Bronze Marble. It should be noted that the photograph, taken in the fall of the year, does not precisely show the true colors for the new and comparison cultivar, with both flowers containing more orange tones than the flowers in actual appearance. However, the color values set forth in the specification hereinbelow are accurate and depict the true color values of both the new and parent cultivars. The color for both cultivars is somewhat lighter under high light, high temperature conditions. Where only a single value or description appears in the following description for the new cultivar, the same value or description applies also to the parent cultivar.

25

65 I claim:

1. A new and distinct cultivar of daisy form chrysanthemum characterized particularly as to its uniqueness when compared to the parent cultivar Bronze Marble by its darker, more intense bronze color.
